(57) **CLAIM**

The ornamental design for a centrifuge, as shown and described.

DESCRIPTION

FIG. 1 is a front, top perspective view of a centrifuge comprising the new design;

FIG. 2 is a back, bottom perspective view of the design of FIG. 1;

FIG. 3 is a front elevational view of the design of FIG. 1;

FIG. 4 is a back elevational view of the design of FIG. 1;

FIG. 5 is a left elevational view of the design of FIG. 1;

FIG. 6 is a right elevational view of the design of FIG. 1;

FIG. 7 is a top view of the design of FIG. 1;

FIG. 8 is a bottom view of the design of FIG. 1;

FIG. 9 is a front, top perspective view of an alternative embodiment of the centrifuge of FIG. 1;

FIG. 10 is a back, bottom perspective view of the design of FIG. 9;

FIG. 11 is a front elevational view of the design of FIG. 9;

FIG. 12 is a back elevational view of the design of FIG. 9;

FIG. 13 is a left elevational view of the design of FIG. 9;

FIG. 14 is a right elevational view of the design of FIG. 9;

FIG. 15 is a top view of the design of FIG. 9; and,

FIG. 16 is a bottom view of the design of FIG. 9.

The broken lines depict portions of the centrifuge that form no part of the claimed design; the broken lines form no part of the claimed design.
